UNITED STATES PATENT OFFICE.

JOSEPH M. DENNING, OF DENVER, COLORADO.

FENCE MACHINE.

Application filed March 7, 1925. Serial No. 13,728.

This invention has to do with improvements in machines for manufacturing fencing of the type in which vertical pickets are connected together by a series of longitudinal strand wires. Fencing of this kind is used for many purposes including the fencing of yards for chickens, and other domestic animals, etc.

The main object of the invention is to provide in machines of this type mechanism for trimming the ends of the pickets so as to point them and finish them.

In connection with the above, it is an object to provide means for pointing the pickets after they have been joined together in the continuous fence.

Machines capable of accomplishing this general result have heretofore been provided as, for example, that disclosed in Letters Patent of the United States No. 1,340,530 issued to me May 18, 1920, on my application filed March 17, 1919. The type of machine therein disclosed includes knives for pointing the end portions of the pickets by a movement transverse to the pickets themselves and involves the use of certain mechanisms which, in some cases, cannot be conveniently applied to the fence machine proper.

The main object of the present invention is to provide means for pointing the pickets by the use of cutters which are movable lengthwise of the individual pickets as distinguished from the transverse movement of my earlier patent.

Another object in connection with the above is to provide a very simple construction of mechanism for accomplishing the above result and one which will be very positive in its operation.

A further object is to provide a pointing mechanism which can be very conveniently and readily applied to picket fence machines of the construction and arrangement already in use.

Other objects and uses of the invention will appear from a detailed description of the same, which consists in the features of construction and combinations of parts hereinafter described and claimed.

In the drawings:

Figure 1 shows a plan view of the ma-

chine embodying the features of the present invention;

Fig. 2 shows a vertical elevation on the line 2—2 of Fig. 1, looking in the direction of the arrows and on enlarged scale;

Fig. 3 shows a fragmentary plan view of the picket pointing mechanism with the other portions of the machine removed, and on enlarged scale as compared to Figs. 1 and 2, the ends of some of the pickets being broken off, and the pointing mechanism standing in the idle position;

Fig. 4 shows an elevation on the line 4—4 of Fig. 3, looking in the direction of the arrows;

Fig. 5 shows a fragmentary vertical section on the line 5—5 of Fig. 4, looking in the direction of the arrows, but on enlarged scale;

Fig. 6 shows a view similar to that of Fig. 3, with the exception that the cutting jaws have been forced forward so as to trim the edges of the end of the picket to point the same;

Fig. 7 shows on enlarged scale a fragmentary view of the cutting jaws in the position of Fig. 3;

Fig. 8 shows an elevation corresponding to Fig. 7; and

Fig. 9 shows a fragmentary elevation of the pull-off mechanism.

I will now describe the construction and mode of operation of the particular fence machine illustrated in the drawings and to which I have shown the features of the present invention as being applied, since machines of this type are well known and their operation well understood in the art. Moreover, this type of machine is also shown and described in the drawings and specification of the aforesaid Patent No.

1,340,530. I will, however, state in the particular machine illustrated the pickets are fed in from the position 9 of Fig. 1 and travel towards the observer, eventually occupying such positions as those of the pickets 10 and 11 of said figure. The individual pickets are then fed sidewise towards the left to the general position of the picket 12 of Fig. 1, and at the same time the pairs of longitudinal strand wires such as 13 are twisted about the picket in proper spaced relationship. The completed fence

ing is then drawn away from the observer towards the position 14 of Fig. 1.

The pickets are initially unpointed and have squared ends at both ends. It is the 5 main object of the present invention to provide mechanism for pointing the pickets.

According to the present invention I provide a pair of cutting blades 15 and 16 having vertical front cutting edges, so that upon 10 moving said blades forwardly in the proper path of travel they will trim the sides of the end portion of the picket or slat to give a curved point.

For the above purpose, the blade 15 is 15 placed vertically at the end of a hook shaped arm 17 (see Figs. 7 and 8). In like manner the blade 16 is placed vertically at the end of another arm 18 opposite to the position of the arm 17. Both of the arms 17 and 18 20 are pivoted on the vertical pins 19 and 20 of a rock bar 21. The arm 18 is placed at a lower level than the arm 17 and is almost straight, whereas the arm 17 at a higher level is curved or hooked backwardly as 25 clearly evident from Fig. 7 in particular. This is for the purpose of allowing both of the arms to swing back and forth so as to move the jaws lengthwise of the picket, without interference between the arms themselves. By this arrangement also I have provided for movement of the blades in curved 30 arcs established about centers at the opposite sides of the picket from the positions of the blades themselves. Thus the blade 35 15 is at the opposite side of the picket from its pivotal point 19, and the blade 16 is at the opposite side of the picket from its pivotal point 20. Furthermore, the circular arcs for both blades are of substantially the 40 same diameter, so that both edges of the picket are similarly trimmed.

The bar 21 is carried on top of a pair of side plates 22 and 23 which embrace between them a relatively long bar 24, as 45 clearly illustrated in Figs. 4 and 5. The bar 24 in turn is pivoted to the frame bar 25 at the pivotal point 26.

The free end of the bar 24 is connected 50 with the free end of another bar 27, by a link 28. The bar 27 is pivoted to a frame bar or bracket 29 at the pivotal point 30, so that upon depressing the free end 31 of the bar 27 the rectangular frame thus established will be raised and thus raise the 55 blades 15 and 16.

For the above purpose a cam 32 is placed 60 on one of the main operating shafts 33 of the machine, which shaft makes one complete revolution for each picket set into place. Consequently, the bar 21 together with the cutting blades will be raised and lowered once for each picket set into place in the fencing.

The foregoing mechanism is for the purpose of allowing the blades to be dropped

down out of the path of travel of the pickets between cutting operations, so that the completed fencing can be advanced in proper timed relationship. The cam 32 is so positioned and timed that it will raise the 70 blades to the sides of the picket at the time when the picket occupies the proper position in its travel. While so raised, the blades are moved for the cutting operation and then they are again lowered away from the 75 path of picket travel for the reason already explained.

Within the body of the machine is placed a link 34 the front end 35 of which is connected to the end portion of the arm 18 by 80 a pivotal connection 36. The front end of the link 34 is also connected to the end portion of the arm 17 by a link 37 with a pivotal connection 38 to the arm 34, and another pivotal connection 39 to the arm 17. 85

A bell crank 40 is pivoted to a stationary point by a pin 41. One arm of this bell crank is pinned to the inner end of the link 34 and the other arm of the bell crank connects by a link 42 with the upper end of 90 a rock arm 43. The lower end of said rock arm is pivoted to a frame bracket 44 at the point 45. A cam 46 is placed on the shaft 33 and may work against a roller 47 carried by the central portion of the arm 43. A 95 spring 48 draws the arm 43 to the right in Fig. 4, so as to maintain the roller against the cam at all times.

The connections of the link 34 with the bell crank and with the arms 17 and 18 are 100 sufficiently free and establish sufficient play to allow the bar 21 together with the blades to be raised and lowered as already explained without binding. Nevertheless, positive connections are maintained between the 105 parts at all times.

The cam 46 is so shaped and timed that 110 after the cutting blades have been raised at the sides of the stationary picket, the arm 43 is rocked towards the left so as to swing the bell crank and force the cutting blades 115 forwardly in the cutting operation, as clearly evident from Fig. 6, which illustrates this condition. Furthermore, the amount of movement occasioned by the cam and roller connection should be such that the cutting blades are just brought together at the completion of every stroke so as to insure full trimming of the picket.

It will be noted that the plates 22 and 23 120 are slidably mounted upon the bar so that when the cutting blades 15 and 16 have been raised at the sides of the picket, the plate 21, together with the blades and connected mechanism, may slide with respect to the bar 24 in the direction of fence travel. This 125 makes it possible for the blades to perform their cutting operation at the same time that the fencing is being advanced toward the left, so that the cutting operation can be per-

formed in a machine for the continuous manufacture of fencing.

A spring 49 is being provided for drawing the blades 22 and 23 and connected mechanism back to the initial position after the cutting blades are dropped away from the picket, such initial position being established by a stop pin 50 on the bar 24.

The fencing may be drawn off in any convenient manner, but the pull-off mechanism illustrated in Fig. 9 is a convenient one to use. The same includes a pulling drum 51 preferably comprising a series of plates secured across a shaft 52 which revolves in a definite relation to the balance of the machine. A series of angle bars 53 extend across and are secured to the edges of these plates. These angle bars are spaced at the same spacing as the pickets of the completed fencing. Such angle bars are also notched to receive the longitudinal strand wires 13 so that the pickets can lie between the angle bars as clearly evident from Fig. 9. With this arrangement the drum 51 will serve as a very satisfactory tension drum for drawing the fencing toward the left.

An idle roller 54 serves to deliver the fencing to the drum 51, and another idle roller 55 serves to deliver the fencing from the drum 51 to a winding drum 56. The drum 56 is preferably driven by a chain 57 from a suitable power shaft. A slip connection, such as a clutch 58, is established between the power shaft and the chain 57, so that as the fencing winds upon the drum 56 and the diameter increases, the clutch can slip sufficiently to compensate for such increased diameter.

It will be seen from the foregoing, that in this present machine I have provided means for trimming the end portions of the pickets by a cutting operation parallel to the length of the pickets as distinguished from previous constructions in which the cutting operation has been by a movement transverse with respect to the picket.

While I have herein shown and described only a single embodiment of the features of the present invention, still I do not intend to limit myself to the same, except as I may do so in the claims.

I claim:

1. In a machine for the manufacture of picket fencing, having cross pickets together with longitudinally extending strand wires joining said pickets together, the combination of means for continuously advancing the fencing in the direction of the strand wires, a frame bar mounted for movement towards and from the line of travel of the pickets of said fencing, a pair of cutters on said frame bar movable parallel to the length of the pickets, means for raising the frame bar to present the cutters at the sides of a picket, and means for moving the cut-

ters longitudinally of the picket to thereby trim the sides of the picket, substantially as described.

2. In a machine for the manufacture of fencing having transverse pickets and longitudinally extending strand wires, the combination of means for continuously advancing the fencing in a direction parallel to the strand wires, a blade carrier, means for moving the same towards and from a picket while the fencing is moving, and means for moving the blades longitudinally of the picket while the fencing is moving to thereby trim the sides of the picket, substantially as described.

3. In a machine for the manufacture of pickets and the like, the combination of a pair of blades mounted to occupy positions at the sides of the picket, overlapping arms on which the blades are carried, pivotal mountings for the arms at the sides opposite to the positions of the respective blades, and a link connection with the overlapping arms for swinging both of the blades on their respective pivotal mountings in a direction longitudinal with respect to the picket to thereby trim the edges of the pickets on circular arcs, substantially as described.

4. In a machine for the trimming of pickets, the combination of means for feeding successive pickets to position to be trimmed, a pair of blades mounted to occupy positions at the sides of the picket, means for causing said blades to travel convergingly toward each other as they are moved toward the end of the picket, and means for moving the blades toward the end of the picket to thereby trim the sides of the picket, substantially as described.

5. In a machine for the manufacture of fencing having transverse pickets and longitudinally extending strand wires, the combination of a pair of blades adapted to occupy positions at the sides of the picket, pivotal mountings for the blades at the sides opposite to the positions of the blade, means for shifting the blades and pivotal mountings into position adjacent to the picket, and means for swinging both of the blades on their respective pivotal mountings in a direction longitudinal with respect to the picket to thereby trim the edges of the picket on circular arcs, substantially as described.

6. In a machine for the manufacture of fencing having transverse pickets and longitudinally extending strand wires, the combination of a pair of blades adapted to occupy positions at the sides of the picket, means for causing said blades to travel in circular arcs towards each other as they are moved towards the end of the picket, and means for moving the blades towards the end of the picket to thereby trim the sides of the picket, substantially as described.

JOSEPH M. DENNING.
